(57) **CLAIM**

The design for a smart device holder, as shown and described.

DESCRIPTION

FIG. 1 is a front perspective view of the smart device holder; FIG. 2 is rear perspective view of the smart device holder of FIG. 1;

FIG. 3 is a top view of the smart device holder of FIG. 1; FIG. 4 is a bottom view of the smart device holder of FIG. 1;

FIG. 5 is a front view of the smart device holder of FIG. 1; FIG. 6 is a side view of the smart device holder of FIG. 1; FIG. 7 is a side view of the smart device holder of FIG. 1; and,

FIG. 8 is a rear view of the smart device holder of FIG. 1.
